HOLDING DEVICE

William Carter and William T. Clarke,
New Bedford, Mass.

Application February 6, 1946, Serial No. 645,871

8 Claims. (Cl. 242—130)

1

This invention relates to the production of synthetic fibers such as rayon, and more particularly to a device for supporting the fiber during rewinding after its initial formation.

In the manufacture of synthetic fiber, such as yarn or thread, of rayon or like material, a common practice is to collect the newly spun fiber to form a loosely wound hollow cylinder or coil known in the trade as a cake or cheese. This coil is relatively heavy, for example 1½ pounds, and contains very substantial yardage, depending upon the size or denier of the fiber. For example, in the case of 300 denier the cake will include approximately 22,000 yards, and for 75 denier as much as 88,000 yards. In the further treatment of the fiber it is commonly rewound upon a suitable device such as a cone or bobbin, and during this rewinding the cake should be handled with care to avoid breakage of the fiber and resultant loss. The cake itself is quite soft, and since it is formed with a hollow core, it will collapse on itself unless it is properly supported, and the fiber breaks quite easily and also tends to tangle and snarl quite readily and is difficult to untangle without breaking, these difficulties increasing as the cake is unwound and becomes thinner and looser. The present invention is concerned with the provision of means for supporting the cake and fiber during the rewinding operation.

One of the principal objects of the invention is to provide a device for holding a cake of rayon or like fiber during rewinding which will be relatively simple both to manufacture and to use, and which in use will substantially eliminate loss of fiber resulting from breakage or tangling during rewinding.

A further object is to provide a device for the above purpose adopted for insertion in the core of a cake of rayon or like fiber to hold the same during rewinding and which will exert substantially constant and uniform pressure radially outward against the inner wall of the cake and so hold and support the cake as the fiber is unwound therefrom.

Another object is to provide a device for the above purpose which includes an elongated inflatable and deformable member which can be inserted in the core of a cake of rayon or like fiber and then inflated with a pressure fluid to fill out and support the cake as the fiber is unwound therefrom.

It is also an object to provide a device for the above purpose which includes means for holding the generally tubular stocking member which is

2

commonly inserted in the core of a cake of rayon or like fiber after spinning and for preventing the fiber from catching or snagging on this stocking during rewinding.

5 A further object is to provide a device for the above purpose which will operate effectively throughout the rewinding operation and including the end of the operation when only a few strands of fiber remain on the cake.

10 Other objects and advantages will be apparent from the following description, the accompanying drawings, and the appended claims.

In the drawings, which illustrate a preferred embodiment of the invention and in which like 15 reference characters designate like parts throughout—

Fig. 1 is a view in side elevation illustrating the use of a device embodying the invention to hold a cake of rayon or other fiber during rewinding of said fiber;

20 Fig. 2 is an exploded perspective view illustrating in more detail certain of the elements shown assembled in Fig. 1;

Fig. 3 is a side elevation, partly in vertical section, illustrating an intermediate stage in setting up for use the holder device and cake shown in Figs. 1 and 2;

25 Fig. 4 is a bottom view of the holder device shown in Figs. 1 to 3;

Fig. 5 is a fragmentary section taken substantially on the line 5—5 in Fig. 4; and

30 Fig. 6 is a view in vertical section of a modified form of the cap member shown in Figs. 1 and 2.

35 In the drawings, the element designated generally by the reference character 10 represents a cake of the type described above and is shown as composed of fiber or yarn 11 of rayon or similar material. This fiber is newly formed, the cake being shown as having a hollow core indicated at 12 and also as provided with a protective cover 13 or "stocking." This stocking commonly is in the form of a tube-like length of fabric, usually of stockinette weave to give elasticity, which is drawn through the core 12 of the cake promptly after the latter is formed and then folded back at both ends on the outside of the cake with the ends 13a and 13b overlapping each other as shown particularly in Fig. 2.

40 45 A base member 14, shown as comprising an annular plate of wood, should be of sufficient size to provide an adequate supporting surface for cake 10, satisfactory results having been obtained using a base member of a diameter slightly greater than the maximum diameter of the cake,

An inflatable member 15 is secured at one end to base member 14 and is adapted for insertion in hollow core 12 of cake 10. This member 15 is so constructed and shaped that when it is so inserted within the core of the cake and inflated with a suitable fluid, such as compressed air, it will expand in such manner so to conform yieldably to the inner configuration of the cake and exert a gentle but substantially uniform radial pressure outwardly against the cake and throughout the entire axial length thereof. The material of which member 15 is composed should be sufficiently strong so that when inflated to this desired amount, the member 15 will be self-supporting to a degree sufficient to provide adequate support also for cake 10 throughout unwinding of the fiber therefrom. For example, satisfactory results have been obtained with conventional rayon cakes using a member 15 of the size and shape of a standard bladder for a rugby football and made of a corresponding grade of relatively heavy rubber.

Fig. 5 illustrates in detail means for securing inflatable member 15 to base member 14. As shown, the lower end of member 15 is partially doubled back on the remainder of the member at 16 and inserted in a central aperture in base member 14. A circular plug 17 of wood or other suitable material is similarly inserted in this aperture and is of a diameter slightly less than that of the aperture so that the doubled portion 16 of member 15 may be clamped between its outer sides and the sides of the aperture. This joint may if desired be further secured by suitable adhesive material, and it will also be noted that the upper surface 18 of plug 17 is preferably rounded off to avoid presenting sharp corners to inflatable member 15. If the diameter of the central aperture in member 14 is equal to or slightly greater than the inner diameter of cake 10, member 15 when inflated will readily assume the desired size and shape conforming to the inner configuration of the cake as described.

A bottom plate 19 of plastic, wood, Masonite or the like may be secured as by screws 20 to the bottom of member 14 and provides a more finished appearance. A valve stem 21 containing suitable valve means, such as are conventionally utilized with the ordinary inner tubes and the like, is suitably secured to member 15 and provides for inflation and deflation thereof. Valve stem 21 is shown as extending out through a suitable aperture in members 14, 17 and 19 and held by a suitable locking nut 22. The bottom of the base member also has secured thereto as by means of screws 23 a plurality of substantially radially arranged spring fingers 24, each of which carries on its outer end a generally rounded member 25 of wood, plastic or the like. These members serve to hold the lower end 13a of stocking 13 when the device is in use, as will be described.

In using this device, inflatable member 15 is first inserted in hollow core 12 of cake 10, preferably while deflated to permit ready insertion without disarranging the fiber in the cake. The stocking 13 also aids in protecting the fiber along the inner wall of the cake against disarrangement as the inflatable member is inserted into place. Fig. 2 shows these parts just prior to the insertion step, the member 15 when inserted projecting loosely into the center of the cake. Member 15 is then inflated by means of an air pump or other suitable source of pressure fluid. As described, member 15 should be sufficiently

inflated to expand it to fill the hollow core of cake 10 and exert the desired pressure radially outward on the cake, the degree of inflation, however, being controlled to avoid exerting tension on the fiber such as might cause undesirable stresses or breakage. This stage in the assembly and use of the device is shown in Fig. 3, and it will be noted that the portion of member 15 within the cake has assumed a substantially cylindrical shape and is in contact with the inner surface of cake 10 along substantially the entire axial length thereof.

After member 15 has been inflated as described, lower end 13a of stocking 13 may be drawn down from around the cake and held out of the way by means of the catch members provided by spring fingers 24 and their rounded heads 25, as indicated in Fig. 1. The upper end 31b of the stocking may then be similarly drawn up from around the cake, and a cap member is provided for holding this end of the stocking out of the way.

The cap member shown in Figs. 1 and 2 comprises a hollow portion 30 of plastic or other suitable material having the general shape of the frustum of a cone, and an annular flange or rim portion 31 integral with or otherwise secured to the base of the cap. The dimensions of this cap are preferably such that it is adapted to enclose and seat on the upper end of inflatable member 15, by means of which it is supported out of contact with the upper end of cake 10 to avoid exerting pressure axially thereon. This construction provides that the cap can be set in position after the upper end 13b of stocking 13 is drawn up off the cake and will thus hold the stocking out of the way and so prevent the fiber from catching thereon during unwinding. If the internal dimensions of the cap member are slightly less than the corresponding dimension of member 15 when inflated, the weight of the cap will slightly compress the upper end of member 15 and so help to maintain the desired expanding pressure in the position of member 15 within the cake. In the normal use of the device, the cake is usually positioned vertically and fiber 11 drawn off substantially vertically therefrom, as indicated in Fig. 1. If, therefore, rim portion 31 of the cap has a diameter at least equal to the maximum diameter of the cake before unwinding, it will provide a guide for fiber 11 during unwinding which both helps to draw the fiber radially from the cake to prevent tangling and also maintains a constant course for the fiber to the member on which it is being rewound. The outer edge 32 of rim portion 31 may be rounded or beaded to facilitate this action.

Fig. 6 shows a modified form of cap member in which the upper portion 35 is generally cup shaped and closed at its upper end and is secured by means of a suitable hinge 36 to the annular rim portion 37. With this form of cap member, the inner diameter of rim portion 37 should be sufficiently less than the diameter of member 15 when inflated to provide that the cap member will be maintained spaced above the cake when placed in proper position on the upper end of the inflated member 15, as described. With this construction, the upper end of the stocking can be pulled through the inner diameter of rim member 37 and the cap properly seated on the inflated member 15 with upper portion 35 swung back out of the way. Thereafter the upper cap portion 35 can be closed down against the rim

portion, thus completely enclosing the upper end of the stocking.

Fig. 1 illustrates the above device completely assembled as described for the rewinding of cake 10, and it will be understood that as so assembled the device is readily adapted for use with or mounting on any machine wherewith cakes of the above type are used, such as a cone winder or the like. As so assembled and used, the device has been found to operate with a high degree of efficiency. With the inflated member 15 constructed as described, it supports the cake effectively throughout the entire rewinding operation. Since the outer diameter of the cake decreases as the fiber unwinds, the ability of the cake to support itself correspondingly decreases, which would ordinarily increase the tendency of the fiber to loosen and hence to tangle or strip off the cake in loops. The device of the invention prevents this result since as the cake becomes thinner, its restraining force on the inflated member is decreased, and the latter can expand sufficiently to tighten the fiber remaining in the cake against slipping and tangling. At the same time, however, since the walls of member 15 are deformable in all directions, any excess pressure can be relieved by expansion at areas from which the fiber has been unwound, thus preventing tension on the remaining which could otherwise cause undesirable stress or breakage. These features in the use of the inflatable member materially reduce the chance of tangling, and the above provision of means for retaining the stocking out of the path of the fiber is also helpful in preventing catching of the fiber thereon, which with other holding devices is a frequent cause of breakage. In practice it has been found that with this device tangling occurs so rarely that the over-all loss of fiber from breakage during rewinding averages not more than a small fraction of one percent of the total fiber in the cake and is frequently wholly eliminated.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A device for holding an annular cake of fiber during rewinding, said cake having a substantially tubular stocking member inserted in the core thereof, said device comprising, in combination, an annular base member, an elongated inflatable member secured at its lower end to said base member and adapted for insertion in the core of said cake, means carried by said base member for holding the lower end of said stocking member, a cap adapted for mounting on the upper end of said inflatable member and cooperating therewith to hold the upper end of said stocking, and means providing for inflation and deflation of said inflatable member and including valve-controlled tube means communicating with the interior of said inflatable member and projecting through said base member.

2. A device for holding an annular cake of fiber during rewinding, said cake having a substantially tubular stocking member inserted in the core thereof, said device comprising, in combination, an annular base member, an elongated inflatable member secured at its lower end to said base member and adapted for insertion in the core of said cake, means comprising a plurality

of resilient catch members substantially radially arranged on the lower surface of said base member for holding the lower end of said stocking member, and means providing for controlled inflation of said inflatable member.

3. A device for holding an annular cake of fiber during rewinding, said cake having a substantially tubular stocking member inserted in the core thereof, said device comprising, in combination, a base member, an elongated inflatable member secured at one end to said base member and adapted for insertion in the core of said cake, means providing for controlled inflation of said inflatable member, and a cap member adapted for removable engagement with the end of said inflatable member opposite said base member providing a guide for fiber unwinding from said cake and cooperating with said inflatable member to hold the upper end of said stocking out of the way of said unwinding fiber.

4. A device for holding an annular cake of fiber during rewinding, said cake having a substantially tubular stocking member inserted in the core thereof, said device comprising, in combination, a base member, an elongated inflatable member secured at its lower end to said base member and adapted for insertion in the core of said cake, a cap member adapted for removable engagement with the upper end of said inflatable member and cooperating therewith to hold the upper end of said stocking out of the way of fiber being unwound from said cake, said cap member including an annular rim portion not substantially less in diameter than the maximum diameter of said cake, providing a guide for fiber being unwound from said cake, and means providing for inflation and deflation of said inflatable member and including valve-controlled tube means communicating with the interior of said inflatable member and projecting through said base member.

5. A device for holding an annular cake of fiber during rewinding, said cake having a substantially tubular stocking member inserted in the core thereof, said device comprising, in combination, an annular base member, an elongated inflatable member secured at its lower end to said base member and adapted for insertion in the core of said cake, a plurality of resilient catch members substantially radially arranged on the lower surface of said base member for holding the lower end of said stocking member, a cap member adapted for removably enclosing the upper end of said inflatable member and holding the upper end of said stocking member, said cap member including an annular rim portion at least equal in diameter to the maximum diameter of said cake, said rim providing a guide for fiber being unwound from said cake, and means providing for inflation and deflation of said inflatable member and including valve-controlled tube means communicating with the interior of said inflatable member and projecting through said base member.

6. The combination comprising an annular cake of fiber to be unwound, said cake having a substantially tubular stocking member inserted in the core thereof, and a holder for said cake comprising a base member, an inflatable member secured at its lower end to said base member, said cake being supported on said base member and said inflatable member being inserted in the core of said cake, said inflatable member being inflated with pressure fluid and exerting pressure radially outward on said cake from the

core thereof, means for holding the upper end of said stocking member out of the way of fiber unwinding from said cake, and means carried by said base member for holding the lower end of said stocking member.

7. The combination comprising an annular cake of fiber to be unwound, said cake having a substantially tubular stocking member inserted in the core thereof, and a holder for said cake comprising a base member, an inflatable member secured at its lower end to said base member, said cake being supported on said base member and said inflatable member being inserted in the core of said cake, said inflatable member having a valve controlled orifice providing for inflation and deflation thereof, said inflatable member being inflated with pressure fluid and exerting pressure radially outward on said cake from the core thereof, a plurality of resilient catch members substantially radially arranged on the lower surface of said base member for holding the lower end of said stocking member, and a cap member enclosing the upper end of said inflatable member and holding the upper end of said stocking member, said cap member including an annular rim portion at least substantially equal in diameter to the maximum diameter of said cake, said rim providing a guide for fiber being unwound from said cake, and means providing for inflation and deflation of said inflatable member and including valve-controlled tube means communicating with the interior of said

10

8
inflatable member and projecting through said base member.

8. In combination with an annular cake of fiber of rayon or the like, a holding and supporting device comprising a base adapted to receive the cake thereon, a stocking extending through the hollow core of said cake in protective relation thereto, a member supported on said base and extending within said hollow core and stocking, said member having yielding and deformable walls expanded by internal fluid pressure into uniform gentle contact with the inner wall of said cake to retain said cake firmly upon said base as the fiber is unwound therefrom, means cooperating with the upper end of said member to hold the upper end of said stocking out of the way of fiber unwinding from said cake, and means carried by said base for holding the lower end of said stocking.
